(57) **CLAIM**

The ornamental design for a passenger car, as shown and described.

DESCRIPTION

FIG. 1 is a front view of a passenger car showing our new design;

FIG. 2 is a rear view thereof;

FIG. 3 is a top plan view thereof;

FIG. 4 is a left side elevational view thereof;

FIG. 5 is a right side elevational view thereof; and,

FIG. 6 is a front right perspective view thereof.

The shading applied on the entire surface area of each figure represents the shape of the three-dimensional surface. The part of the article corresponding to the window glass of the design is translucent.

1 Claim, 6 Drawing Sheets
